UNITED STATES PATENT OFFICE.

THOMAS H. RODMAN, OF NEW YORK, N. Y., ASSIGNOR TO THE CUTLER-HAMMER MFG. CO., OF MILWAUKEE, WISCONSIN, A CORPORATION OF WISCONSIN.

MOTOR CONTROLLER.

Application filed February 21, 1921. Serial No. 446,655.

To all whom it may concern:

Be it known that I, THOMAS H. RODMAN, a citizen of the United States, residing at New York, in the county of New York and State 5 of New York, have invented new and useful Improvements in Motor Controllers, of which the following is a full, clear, concise, and exact description, reference being had to the accompanying drawing, forming a 10 part of this specification.

This invention relates to motor controllers and while not limited thereto is particularly applicable to controllers for printing presses.

In my copending application, Serial No. 15 406,505, filed August 27, 1920, there is disclosed a controller particularly designed for printing press service wherein provision is made to necessitate operation of a special safety switch prior to restarting by the usual 20 starting means following stopping by other than the inching means. More specifically such controller is provided in addition to the usual "on" and "inch" push button switches with a so-called "reset" push button 25 ton switch and the arrangement is such that when the press is stopped in any one of various ways the "reset" button must be pressed prior to starting by either the "on" or "inch" buttons. However, the arrangement 30 enables inching in the usual manner after once depressing the "reset" button, i. e., without repeated depression of the latter button for each step of inching operation.

The present invention has among its objects to provide a controller including similar control instrumentalities co-ordinated to further require depression of the "reset" button for each step of inching operation.

Another object is to provide for such co-ordination of elements when so desired by a 40 very slight modification of the controller disclosed in my aforementioned copending application.

Another object is to provide for co-ordination of the elements either to necessitate starting within a limited period following operation of the "reset" switch or to permit delayed starting following operation of the reset switch, as may be desired.

50 Other objects and advantages of the invention will hereinafter appear.

The accompanying drawing illustrates a controller embodying the invention in one form and the same will now be described, it being understood that the controller illustrated is susceptible of various modifications without departing from the scope of the appended claims.

In the drawing,

Fig. 1 is a diagrammatic view of the controller;

Fig. 2 is a so-called "across-the-line" diagram illustrating the preferred motor connections;

Figs. 3 to 5 are similar diagrams illustrating certain of the circuit connections of Fig. 1 in a manner to facilitate an understanding thereof; and

Fig. 6 is a diagrammatic view illustrating a modification.

Referring to Fig. 1 the controller illustrated therein is, with certain additions, identical with that disclosed in my copending application aforementioned being designed for a double motor drive shown in Fig. 2 as comprising a small motor M and a large motor M'. This controller comprises an electro-responsive main switch 1 for the small motor, an electro-responsive main switch 2 and dynamic brake switch 3 for the large motor and a crosshead type rheostat R driven by a pilot motor M² to control said switches and to further control an armature resistance r and a field resistance r' for the large motor M', the resistance r being omitted from Fig. 1 but its contacts being illustrated therein and designated by the same reference character. An "on" relay 4 is provided to effect operation of the pilot motor for starting the motors M and M' successively and for accelerating the latter while an "off" relay 5 is provided to effect reverse operation of the pilot motor. Also the controller includes a "stop" relay 6 to stop both motors, an "inch" relay 7 to start and stop the small motor M, a "safe" relay 8 to render all of the aforesaid relays inoperative, a "paper-break" relay 9, and signal relays 10 and 11, all of said relays being under the control of a push-button station

comprising an "on" switch 12, a "stop" switch 13, an "off" switch 14, a "safe" switch 15, a "reset" switch 16, a "stop" switch 17, a "safe" switch 18, a "reset" switch 19, a "stop" switch 20, a "safe" switch 21, a "reset" switch 22, a "stop" switch 23, a "safe" switch 24, a "reset" switch 25, a "stop" switch 26, a "safe" switch 27, a "reset" switch 28, a "stop" switch 29, a "safe" switch 30, a "reset" switch 31, a "stop" switch 32, a "safe" switch 33, a "reset" switch 34, a "stop" switch 35, a "safe" switch 36, a "reset" switch 37, a "stop" switch 38, a "safe" switch 39, a "reset" switch 40, a "stop" switch 41, a "safe" switch 42, a "reset" switch 43, a "stop" switch 44, a "safe" switch 45, a "reset" switch 46, a "stop" switch 47, a "safe" switch 48, a "reset" switch 49, a "stop" switch 50, a "safe" switch 51, a "reset" switch 52, a "stop" switch 53, a "safe" switch 54, a "reset" switch 55, a "stop" switch 56, a "safe" switch 57, a "reset" switch 58, a "stop" switch 59, a "safe" switch 60, a "reset" switch 61, a "stop" switch 62, a "safe" switch 63, a "reset" switch 64, a "stop" switch 65, a "safe" switch 66, a "reset" switch 67, a "stop" switch 68, a "safe" switch 69, a "reset" switch 70, a "stop" switch 71, a "safe" switch 72, a "reset" switch 73, a "stop" switch 74, a "safe" switch 75, a "reset" switch 76, a "stop" switch 77, a "safe" switch 78, a "reset" switch 79, a "stop" switch 80, a "safe" switch 81, a "reset" switch 82, a "stop" switch 83, a "safe" switch 84, a "reset" switch 85, a "stop" switch 86, a "safe" switch 87, a "reset" switch 88, a "stop" switch 89, a "safe" switch 90, a "reset" switch 91, a "stop" switch 92, a "safe" switch 93, a "reset" switch 94, a "stop" switch 95, a "safe" switch 96, a "reset" switch 97, a "stop" switch 98, a "safe" switch 99, a "reset" switch 100, a "stop" switch 101, a "safe" switch 102, a "reset" switch 103, a "stop" switch 104, a "safe" switch 105, a "reset" switch 106, a "stop" switch 107, a "safe" switch 108, a "reset" switch 109, a "stop" switch 110, a "safe" switch 111, a "reset" switch 112, a "stop" switch 113, a "safe" switch 114, a "reset" switch 115, a "stop" switch 116, a "safe" switch 117, a "reset" switch 118, a "stop" switch 119, a "safe" switch 120, a "reset" switch 121, a "stop" switch 122, a "safe" switch 123, a "reset" switch 124, a "stop" switch 125, a "safe" switch 126, a "reset" switch 127, a "stop" switch 128, a "safe" switch 129, a "reset" switch 130, a "stop" switch 131, a "safe" switch 132, a "reset" switch 133, a "stop" switch 134, a "safe" switch 135, a "reset" switch 136, a "stop" switch 137, a "safe" switch 138, a "reset" switch 139, a "stop" switch 140, a "safe" switch 141, a "reset" switch 142, a "stop" switch 143, a "safe" switch 144, a "reset" switch 145, a "stop" switch 146, a "safe" switch 147, a "reset" switch 148, a "stop" switch 149, a "safe" switch 150, a "reset" switch 151, a "stop" switch 152, a "safe" switch 153, a "reset" switch 154, a "stop" switch 155, a "safe" switch 156, a "reset" switch 157, a "stop" switch 158, a "safe" switch 159, a "reset" switch 160, a "stop" switch 161, a "safe" switch 162, a "reset" switch 163, a "stop" switch 164, a "safe" switch 165, a "reset" switch 166, a "stop" switch 167, a "safe" switch 168, a "reset" switch 169, a "stop" switch 170, a "safe" switch 171, a "reset" switch 172, a "stop" switch 173, a "safe" switch 174, a "reset" switch 175, a "stop" switch 176, a "safe" switch 177, a "reset" switch 178, a "stop" switch 179, a "safe" switch 180, a "reset" switch 181, a "stop" switch 182, a 985, a "stop" switch 986, a "safe" switch 987, a "reset" switch 988, a "stop" switch 989, a "safe" switch 990, a "reset" switch 991, a "stop" switch 992,

switch 15, an "inch" switch 16, and a "reset" switch 17. While Fig. 1 shows but a single control station a plurality thereof may be provided as will hereinafter appear.

5 This controller differs from that disclosed in my copending application aforesaid only in the addition of down contacts 7^a provided on the inch switch to control a circuit herein-after described.

10 The switches 1 and 2 are preferably employed to establish the motor connections shown in Fig. 2, each of said switches being of the double pole type and having down contacts coacting to establish a dynamic 15 braking circuit for its respective motor. Each motor is shown as comprising an armature *a*, a series field *f* and a shunt field *f'*, the motor *M'* having in circuit therewith the armature resistance *r* and field resistance *r'* 20 to be controlled by the motor-driven cross-head. Also the motors *M* and *M'* are shown as respectively provided with resistances *r²* and *r³* in the dynamic braking circuits thereof, the motor *M'* having included in the 25 dynamic braking circuit switch 3 which is of the normally closed type.

The "on" and "off" relays respectively establish the circuit connections for the pilot motor shown in Fig. 3, the pilot motor being shown therein as comprising an armature *a* and a series field *f*. Referring to this figure, it will be observed that the "on" relay which is of the double-pole type establishes connections whereby current flows 35 through the armature and field in reverse directions whereas the "off" relay, which is of a similar type establishes connections for a unidirectional flow of current through both the armature and field.

40 The rheostat *R* has a main crosshead 18 and an auxiliary crosshead 19 the former coacting with contacts to control resistance *r* and *r'* and the latter coacting with auxiliary contacts to control the windings of 45 switches 1 to 3 as best illustrated in Fig. 4. This figure shows such auxiliary contacts and as will be observed the auxiliary cross-head 19 in its extreme position serves to connect contacts 20, 21 and 22 for connection of both the small motor switch 1 and 50 large motor dynamic brake switch 3 across the line through the "inch" relay 7, "paper-break" relay 9 and "stop" relay 6, relay 7 being normally open and relays 9 and 6 being normally closed. Thus in this position of the crosshead the small motor may be 55 operated for inching by energizing relay 7. On the other hand when the rheostat is operated crosshead 19 leaves contacts 20, 21 and 22 interrupting the circuit through 60 the "inch" relay and inserting interlocking resistances *r⁴* and *r⁵* in circuit with the windings of switches 1 and 3 respectively to necessitate return of the crosshead to initial 65 position for re-energization of said

switches following de-energization thereof. Upon initial movement of the crosshead 19 the same engages and bridges contacts 23, 24 and 25 which, assuming previous energization of switches 1 and 3, provides maintaining circuits therefor through auxiliary contacts 1^a of switch 1 (Fig. 1). As will hereinafter appear, the "inch" relay is energized by closure of the "on" relay and thus both switches 1 and 3 are energized when 75 the crosshead 19 is first moved and the former switch is maintained energized until said crosshead disengages contact 23. Prior thereto the crosshead 19 engages contact 26 to complete the circuit of the large motor 80 switch through the auxiliary contacts 1^a of switch 1 and before disengaging contact 25 the crosshead engages contact 27 to parallel said auxiliary contacts by auxiliary contacts 2^a of switch 2 (Fig. 1). Thus the 85 auxiliary crosshead provides for starting the motors successively and de-energizing the main switch of the small motor after starting the large motor while maintaining the large motor switches 2 and 3 energized 90 throughout the remainder of its movement, subject of course to de-energization by either the "stop" relay or "paper-break" relay. As will be understood the auxiliary cross-head remains in engagement with contacts 95 24, 26 and 27 during movement of the main crosshead to vary the armature and field resistances of the large motor.

The push button station of Fig. 1 serves to establish the circuit connections shown 100 in Fig. 5, the latter showing duplicate control stations. Referring to Fig. 5 the "on" switches 12 are connected in parallel and each serves to connect the winding of the "on" relay 4 across the line through the 105 normally closed "safe" relay 8 and down limit switch 28 of the rheostat (Fig. 1). Thus the "on" relay 4 is rendered responsive to either "on" switch to complete the pilot motor connections as described while its 110 auxiliary contacts 4^a (Fig. 1) parallel the "inch" switches 16 (Fig. 5) to energize the "inch" relay for starting of the small motor and energization of the dynamic brake switch 3 of the large motor as above set 115 forth.

The "off" switches 14 as shown in Fig. 5 are also connected in parallel and each serves to connect the winding of the "off" relay 5 across the line through the "safe" relay 8 120 and up limit switch 29 of the rheostat (Fig. 1). Thus the "off" relay is responsive to either "off" switch to complete the pilot motor connections as above described for slow down.

The "inch" switches 16 as shown in Fig. 5 have down contacts connected in parallel and either is adapted to be depressed to connect the winding of the "inch" relay 7 across the line through "safe" relay 130

8 whereby the "inch" relay is rendered responsive to start the small motor as above described. Also the "inch" switches 16 have up contacts connected in series and said 5 switches normally connect the winding of the "paper-break" relay 9 across the line through parallel "paper-break" switches 30 each of which is adapted to be normally held open by the paper passing through the

10 press subject to release upon breakage of the paper. Thus with the "inch" switches 16 in normal position release of either "paper-break" switch 30 energizes "paper-break" relay 9 to stop the motors as above 15 described. On the other hand depression of either of the switches 16 for inching interrupts the circuit of the "paper-break" relay thus permitting the press to be inched for rethreading or to be operated at a higher 20 speed if desired by operation of one of the "on" switches 12 in addition to the "inch" switch 16.

The "safe" switches 15 as shown in Fig. 5 are connected in parallel and either is 25 adapted to be set to connect the winding of "safe" relay 8 directly across the line for energization of said relay to disconnect the windings of the "on," "off" and "inch" 30 relays from line L'. Such setting of the "safe" switch thus renders all control stations ineffective to start. However, such setting of the "safe" switch requires a manual operation in addition to the operation of stopping as will appear.

35 The "stop" relay 6 is normally closed (Figs. 1 and 4) and requires depression of a "stop" switch 13 for stopping at will. As shown in Fig. 5, "stop" switches 13 are connected in parallel and either is adapted to be 40 depressed to connect the winding of "stop" relay 6 across the line through upper contacts of the "reset" switches 17 which are connected in series. This energizes the "stop" relay to stop both motors as above 45 set forth and said relay has auxiliary contacts 6^a (Fig. 1) which upon response thereof parallel the "off" switches 14 as shown in Fig. 5 to effect return of the rheostat crossheads to their initial positions. 50 The main switches 1 and 2 for the motors M and M' are respectively provided with auxiliary contacts 1^b and 2^b (Fig. 1) which upon opening of said switches parallel the "stop" switches 13 (Fig. 5) through an up limit switch 31 of the rheostat (Fig. 1) thereby 55 energizing the "stop" relay whenever both motors are stopped as for example by the "paper break" relay.

Thus the "stop" relay is energizable in 60 a number of different ways for stopping and upon response thereof its auxiliary contacts 6^b (Fig. 1) establish a maintaining circuit therefor through the upper contacts of the "reset" switches 17 and a resistance 7^b. In 65 consequence the "stop" relay also functions

automatically as a safe relay requiring operation of one of the "reset" switches 17 to de-energize the same before the motors M and M' can be restarted either by the "on" switch or the "inch" switch. In this connection it is to be understood that any number of "reset" switches may be provided there preferably being one for each control station as shown.

The "reset" switches 17 also have down 75 contacts connected in parallel and each serves when depressed to connect the signal relay 11 across the line through the safe relay 8 as shown in Fig. 5 and this relay as shown in Fig. 1 serves to connect across the 80 line an electric horn 32 or other audible signal device and one or more lamps 33 having in circuit therewith a flasher 34. Thus when either "reset" switch 17 is operated to make ready for starting it functions to give both 85 an audible and a visual signal and it may be operated at any time to give such signal even though its operation is not required for control of the stop relay. As shown the signal relay 11 has down contacts 11^a also functioning to energize the lamps 33 and to shunt the flasher 34 when the press is idle.

90 For additional protection a red light 35 (Fig. 1) is also provided, the same being under the control of relay 10. This relay 95 as shown in Fig. 4 has its winding connected across the line through the "safe" relay 8 on the one side and the "paper-break" and "stop" relays on the other side whereby it is energized to complete the circuit of the red 100 light whenever the controller is ready for starting in response to either the "on" switch or the "inch" switch.

105 As shown in Figs. 1 and 5, the down contacts 7^a which have been added to the "inch" relay 7 parallel the up limit switch 31 wherever said relay is de-energized. Thus it will be apparent that each time said relay is de-energized in inching the "stop" relay is energized thus necessitating depression of one of the "reset" switches prior to restarting. Moreover, it will be apparent that in order to effect restarting the "inch" relay must be energized prior to release of the depressed "reset" switch as 110 otherwise the "stop" relay could and would again respond to establish safe conditions. However, if it is desired to provide for energization of the "inch" relay after release of the depressed reset switch this may be accomplished as for example in the manner depicted in Fig. 6.

115 Referring to Fig. 6 the same shows a portion of the diagram of Fig. 5 the only departure from the arrangement shown in the latter figure consisting in modification of the auxiliary contacts of the "inch" relay. In this instance said contacts comprise an element 7^b co-operating with a contact 7^c to parallel the up limit switch 31 as described. The 120 125 130

contact element 7^b is provided for actuation by the "inch" relay, it being biased to disengage contact 7^c when said relay is de-energized and being movable upon response of said relay to momentarily engage said contact and then disengage the latter. During such operation the engagement of element 7^b with the contact 7^c is too brief to effect response of the "stop" relay but element 7^b is thereby brought to a position to effect its re-engagement with said contact upon de-energization of the "inch" relay and a dash pot 36 is connected to said element to prolong its re-engagement with contact 7^c for effecting response of the "stop" relay.

Thus the contacts 7^b and 7^c function like the contacts 7^a to energize the "stop" relay whenever the "inch" relay is de-energized but unlike contacts 7^a they thereafter assume a position permitting the "reset" switches to be depressed to de-energize the "stop" relay and then released without re-energizing the latter relay regardless of the position of the "inch" relay. Accordingly as the contacts 7^b and 7^c do not engage for a sufficient period of time upon response of the "inch" relay to energize the "stop" relay restarting is not defeated by release of the depressed "reset" switch prior to energization of the "inch" relay.

What I claim as new and desire to secure by Letters Patent is:

1. In a motor controller, the combination with starting and stopping means including manually operable start, stop and inch control elements, of means requiring manual operation of a part thereof to render said start and inch control elements effective for restarting following stopping operation by said inch or stop control elements.

2. In a motor controller the combination with starting and stopping means including a plurality of control stations each having start, stop and inch elements, of a plurality of additional control elements and connections between said means and the latter control elements necessitating operation of one of the same to render said start and inch elements effective for restarting following stopping operation of any one of said inch or stop elements.

3. In a motor controller, the combination with starting and stopping means including a manually operable control element to effect inching, of means requiring manual operation of a part thereof to render said element effective for inching following each stopping operation thereof.

4. In a motor controller the combination with starting and stopping means including a manually operable control element to effect inching, of means requiring manual operation of a part thereof to render the former means effective for restarting following each

stopping operation of said controlling element.

5. In a motor controller, in combination, power operated starting and stopping means, a control station for said means including start, stop, inch and reset control elements and connections between said means and said control station to render said start and inch elements ineffective for restarting following stopping operation of said inch or stop elements but subject to restoration of the effectiveness of said start and inch elements by operation of said reset element.

6. In a motor controller, in combination, power operated starting and stopping means, a plurality of control stations for said means each including start, stop, inch and reset control elements and connections between said means and said control stations to necessitate operation of one of said reset elements prior to restarting by any one of said start or inch control elements following stopping operation of any one of said stop or inch control elements.

7. In a motor controller, in combination, power operated starting and stopping means including a stop relay, a control station for said means including start, stop, inch and reset elements and connections between said means and said station adapted upon stopping operation of said inch or stop elements to cause said relay to move to stop position and to remain in such position but subject to release therefrom at will by said reset element.

8. In a motor controller, the combination with power operated starting and stopping means including a stop relay to be energized for stopping and acting upon continued energization thereof to prevent restarting, of a control station for said means including start, stop, inch and reset switches and circuit connections to effect response of said relay upon stopping operation of said inch or stop switches and to thereupon maintain said relay energized but subject to de-energization of said relay at will by said reset element.

9. In a motor controller, the combination with power operated starting and stopping means including a stop relay to be energized for stopping and acting upon continued energization thereof to prevent restarting, of a plurality of control stations for said means each including start, stop, inch and reset switches and circuit connections to effect energization of said relay upon stopping operation of any one of said inch or stop switches and to thereupon maintain said relay energized but subject to de-energization thereof at will by any one of said reset switches.

10. In a motor controller, the combination with starting and stopping means including a stop relay to be energized for stopping and

an inch relay, of means including a manually controlled element and contacts associated with said inch relay to control said stop relay whereby said relay is maintained energized to prevent restarting following any stopping operation of the first-mentioned

means but subject to de-energization of said relay at will by said manually controlled element.

In witness whereof, I have hereunto subscribed my name.

THOMAS H. RODMAN.
